UNITED STATES PATENT OFFICE.

L. TAYLOR, OF JORDAN, AND J. C. RICHARDSON, OF PRAIRIE DU CHIEN, WISCONSIN.

IMPROVEMENT IN WATER-ELEVATORS.

Specification forming part of Letters Patent No. 95,953, dated October 19, 1869.

To all whom it may concern.

Be it known that we, L. TAYLOR, of Jordan, in the county of Green and State of Wisconsin, and J. C. RICHARDSON, of Prairie du Chien, in the county of Crawford and State of Wisconsin, have invented a new and Improved Water-Drawing Apparatus; and we do hereby declare that the following is a full, clear, and exact description thereof, which will enable others skilled in the art to make and use the same, reference being had to the accompanying drawings, forming part of this specification.

This invention relates to improvements in apparatus for drawing water in buckets from springs or wells situated at long distances from where the water is to be delivered.

The object of the invention is to provide simple and efficient apparatus to be automatically operated by the turning of a crank, to draw the water, convey it to the place for delivery, and to deliver it.

The invention comprises an improved arrangement for drawing water from springs, where the buckets do not have to descend vertically, as in a well, in which arrangement two sets of the carrying apparatus and buckets are employed, one to go forward full while the other goes back empty; also, an improved arrangement of apparatus for drawing from wells, adapted for a vertical descent and ascent of the bucket after the carriage arrives over the well.

Figure 1 represents an elevation, partly in section, of the apparatus as adapted for drawing from a spring. Fig. 2 represents a plan view of the same. Fig. 3 represents a sectional elevation of the apparatus as adapted for drawing from a well. Fig. 4 represents a section taken on the line $x x$ of Fig. 3. Fig. 5 represents a section taken on the line $y y$ of Fig. 3.

Similar letters of reference indicate corresponding parts.

A represents the spring from which the water is to be drawn.

B represents the place of delivery, which may be supposed to be inside the wall C of a house.

D, Fig. 1, Sheet I, represents a track of wire

rods suitably suspended on posts or otherwise between the two points A and B.

E represents a balanced track, bent upward and pivoted at F. This balanced track is for the purpose of allowing two cars to pass, one going down and the other going up.

G H represent the cars. These cars are connected, and to a double pulley, I, and a pulley, K, at the spring by a cord, L. This cord is connected at one end to the groove M of the pulley I, so as to wind thereon when turned to the right. It passes over guide-pulley N to car G, thence around guide-pulley K to car H, thence back over guide-pulley N to groove O of winding-pulley I, so as to wind thereon when turned to the left. The turning of this winding-drum to the left will draw car G down and car H up, and vice versa. In going down car G passes over the balanced track E, and will be about over the pivot F, when the car H, going up, passes sufficiently under the lower end of the said balanced track to allow it to swing over and form the connections for the car G to continue down to the spring, at the same time raising the upper end for the car H to pass up. A similar but reversed movement of the balance-track takes place when the said cars move in opposite directions. These cars carry buckets P, suspended on trunnions of arms Q, between the tracks. The buckets have valves R for closing the openings while passing along the road. These valves are opened by spring-pins S, passing under a guide, T, at the delivery. The buckets are tilted for discharging by pins U on the buckets striking against arms B' rising from the receiving-trough.

In the apparatus for drawing from a well, a similar track, C, Fig. 3, Sheet II, is used; but it is arranged, as is required in some places, for rising up a hill and then passing along a level plain for the balance of the route, under which arrangement it is necessary to provide some means for carrying the bucket back over the said level portion, it not being convenient to employ two buckets in a well and an arrangement of ropes, as above described in the arrangement adapted to springs. The device which we have provided for this purpose consists of a weighted shaft or roller, a, arranged on posts at the end of the level

part of the route, and a bar, *b*, connected to a pulley on the said roller *a* by a cord, *c*², and so arranged that the car *d*, which is provided with hooks *e* for the purpose, will, when being drawn toward the house, engage the bar *b* and carry it along, winding up the cord of the weight, which, when the bucket is discharged and the power detached from the crank-wheel *I*, will react upon the car, drawing it back and discharging it over the crest of the inclined part of the track, whereon its movement will be continued by gravitation to the well. The rod *b* is arrested at the proper time by contact with the posts *f* under the pins *g*. In this arrangement the rope *L'*, passing over a guide-pulley, *N*², in the wall of the house, is passed over a guide-pulley, *h*, on the car, (shown in dotted lines in Fig. 3, Sheet II,) thence under another pulley, *i*, on a stem, *k*, by which the bucket is suspended from the car, thence over another pulley, *i*²; (shown dotted,) and then fastened to the float *m* of the bucket, as shown at *l*. To this stem *k* a float, *m*, is connected so as to hang under the car, and from this, inside of guides *n*, the bucket is suspended on trunnions *q*. These side guides are fitted to work on the vertical rails *r* in the well. The car, on entering the curb over the well, is arrested at the right point to cause these guides, in descending, to engage the said rails. The said stem *k* is suspended from the car *d* by pins connected to spring-levers *t*, which are pressed in to withdraw the pins and disengage the bucket by the moving of the car into the contracted space between the projections *e* of the frame. At the same time the top of the stem passes under the inclined plate *w* and raises it over a ledge or projection, *d'*, behind which it drops or clutches to hold or lock the car while the bucket goes down into the well, which is permitted by the slackening up of the rope *L'*, allowing the bucket to run down to the water and fill. It is tilted for dipping by being journaled eccentrically in the guides *n*. A spring-cover, *x*, closes the mouth of the bucket after filling. The winding up of the rope will first draw the

bucket up and engage it with the car. At the same time the stem *k* will throw the catch *w* up away from the ledge *d'*, leaving the car free to be drawn up the track by the combined winding of the rope.

At *A*², outside of the house, we have arranged a watering-trough for animals, with a tilting discharger, *B*², hinged to the side of it, and provided with a bell crank and cord, *C*², for tilting it up into the path of the bucket *P'*, so that when required the water may be discharged into the said trough. The said discharger *B*² is provided with bent arms *D*², which, when tilted up into the right position, will catch the pins of the bucket and cause it to discharge.

Having thus described our invention, what we claim as new, and desire to secure by Letters Patent, is—

1. The combination of the double-grooved winding-wheel *I*, cord *L'*, cars *G H*, track *D*, and balanced track *E*, when arranged and operating substantially as specified.

2. The combination of the cars *G* or *H*, buckets *P*, spring-pins *S*, valves *R*, and guides *T* *T'*, when arranged and operating substantially as specified.

3. The combination of the track *C'*, Fig. 3, car *d*, weighted roller *a*, bar *b*, and cord *c*², when arranged and operating substantially as specified.

4. The combination of the car *d*, having a ledge, *d'*, stem *k*, and hinged catch-plate *w*, when arranged substantially as specified.

5. The combination of the car *d*, spring-levers *t*, with their pins, stem *k*, and contracting blocks *n'*, when arranged and operating substantially as specified.

6. The combination, with the car *d* and bucket *P'*, of the watering-trough *A* and tilting discharger *B*², substantially as specified.

L. TAYLOR.

J. C. RICHARDSON.
